US00D952668S

(12) **United States Design Patent** (10) **Patent No.:** **US D952,668 S**
Balsamo (45) **Date of Patent:** **** May 24, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventor: **Tito Lloyd Balsamo**, San Francisco, CA (US)

(73) Assignee: **Apple Inc.**, Cupertino, CA (US)

(**) Term: **15 Years**

(21) Appl. No.: **29/817,065**

(22) Filed: **Nov. 29, 2021**

Related U.S. Application Data

(63) Continuation of application No. 29/749,684, filed on Sep. 8, 2020, now Pat. No. Des. 937,306.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
